United States Patent Office.

GEORGE V. FARR AND EPHRAIM HALL, OF BRANDON, VERMONT.

Letters Patent No. 71,726, dated December 3, 1867.

IMPROVED SADDLERS' AND SHOEMAKERS' TOOL.

The Schedule referred to in these Letters Patent and making part of the same.

TO ALL WHOM IT MAY CONCERN:

Be it known that we, GEORGE V. FARR and EPHRAIM HALL, of Brandon, in the county of Rutland, and in the State of Vermont, have invented a new and useful Improvement in Shoemakers' and Saddlers' Channelling Tools; and we do hereby declare that the following is a full, clear, and exact description thereof, which will enable those skilled in the art to make and use the same, reference being had to the accompanying drawing, forming part of this specification, in which drawing—

Figure 1 is a side view of the tool, the principal parts being in section.

Figure 2 is an end view.

Figure 3 is an end view, the cap or spring C being removed from its place over the knife.

This invention relates to tools for cutting "channels" in the soles of boots and shoes, sewed work, and also for channelling small rounds or curves in harness-work, such as cheek-pieces, &c., which have usually been accomplished hitherto by means of a shoe or other knife held in the hand, and gauged as to the depth of the channel or cut by the thumb of the workman. Our invention is described as follows:

The letter A designates a tool-stock, on whose shank is placed a suitable handle. The working end of the stock A is made vertical, as is indicated at O, to form a shoulder that comes against the edge of the sole or other piece of leather that is to be channelled or cut. From the upper edge of the shoulder O the end of the shank is inclined backwards, as is shown in fig. 1, to form a bearing and a place for the attachment of the channelling-knife B, which lies in a groove or channel in the stock, and is secured thereto by a set-screw that goes through an elongated slot cut in the shank of the knife, for the purpose of allowing the knife to be adjusted for the proper depth of the cut or channel. Over the knife we place a spring-cap, C, which is so formed that its forward end is bent down to cover the shank of the knife, a recess being formed on the under side of the bent part to give room for the head of the set-screw that fastens the knife. The rear part or shank of the cap extends along the upper side of the stock, and is fastened thereto by screws D. The shoulder O and the bottom of the lip of the cap C are at right angles to each other, and the knife projects from between them in such a manner as to bisect the said angle, and consequently the said knife, when applied to a sole, will cut into the edge thereof with precision. Both the shouldered end of the stock A and the bottom of the lip of the cap C are rounded or curved transversely to their right-angled faces; that is to say, they are curved in the direction of the motion of the tool when in operation, the object of that provision and construction being to enable the workman to vary the depth of the cut or channel, the knife being set in the middle of the face of the tool, and being tongue-shaped, so that its greatest length is at the middle of its width, and consequently at the centre of the face of the tool.

What we claim as new, and desire to secure by Letters Patent, is—

1. The channelling-tool above described, composed of the adjustable knife B, the stock A, and the spring-cap C, the lip or bottom of the cap, and the shoulder O of the stock, forming a gauge to bring the knife at the edge of the sole to be channelled, substantially as set forth.
2. The rounded or curved forms of the cap C and shoulder O, in the direction of their length, substantially as and for the purpose described.

GEO. V. FARR,
EPHRAIM HALL.
